UNITED STATES PATENT OFFICE.

JOHN EDMUND EASTWOOD, OF ROCKVILLE, CONNECTICUT, ASSIGNOR OF ONE-HALF TO THE SPRINGVILLE MANUFACTURING COMPANY, OF SAME PLACE.

WARPING-REEL.

SPECIFICATION forming part of Letters Patent No. 609,667, dated August 23, 1898.

Application filed October 22, 1897. Serial No. 656,073. (No model.)

To all whom it may concern:

Be it known that I, JOHN EDMUND EASTWOOD, a citizen of the United States of America, residing at Rockville, in the county 5 of Tolland and State of Connecticut, have invented a certain new and useful Improvement in Warping-Reels, of which the following is a description, reference being had to the accompanying drawings, wherein—

10 Figure 1 is a side elevation of a machine embodying the novel parts of said improvement. Fig. 2 is an end elevation of the same machine which is shown in Fig. 1. Fig. 3 is a detail plan view, on an enlarged scale, of the feed-worm and appurtenant pinion. Fig. 4 is a side view of the parts shown in Fig. 3. Fig. 5 is a detail top view of parts having to do with the adjustment of the machine for building warp-sections of different widths. 15 Fig. 6 is a detail view showing, as in a side view thereof, one of the parts shown in Fig. 5.

The object of the invention is the production of a machine for building warp-sections subsequently used, after transference to a 20 warp-beam, in a weaving-loom.

In the accompanying drawings the letter *a* denotes the frame of the machine in general.

The letter *b* denotes the shaft of the rotary warp-reel.

25 *c* denotes the ends of the warp-reel, and *d* denotes the reel-bars, the rotary motion of the warp-reel being given by the belt *e* and common intermediate means.

The reel-shaft carries fixedly thereon the 30 bevel-gear *f*, meshing into a bevel-pinion *g*, borne fixedly on the shaft *h*, carrying the worm *i*, meshing into gear *k*, borne fixedly on the shaft *l*, by means of which train of parts the rotary motion of the warp-reel is communicated to the feed-worm *l*.

The letter *m* denotes a part in shape and construction like a pinion, wherefore it will be called a "pinion" herein. It is fast upon the circular pinion-base *n*, which stands 45 within and is surrounded by a clamp *o*. This clamp *o*, through the medium of diametrically opposite trunnions *p*, rests in the journals *r*, rising from a plate fast on the floor or other support, whereby it is given some latitude of rocking motion in a vertical plane in

order to prevent binding between the worm *l* and pinion *m*, and, if desired, a third trunnion *p'* and journal *r'* may be located at one side of and quartering to the two trunnions and bearings *p* *r* to prevent and limit the 55 rocking of the pinion and clamp in that direction. The clamp *o* may be made to tightly grasp the pinion-base and hold it and the appurtenant pinion from rotation by proper setting of the clamp-screw *s*, and by reverse 60 manipulation of the same the clamp may be released from its grasp of the pinion-base and its appurtenant pinion, leaving that pinion free to rotate. It is obvious that when the feed-worm *l* rotates and the pinion *m* is secured against rotation the effect will be to move the entire machine longitudinally in the direction indicated by the arrow overlying the feed-worm, the machine being mounted upon the rails *t*, through the medium of the 65 rollers *u*, for that particular purpose.

The letter *v* denotes warp-attachment pins fast in and projecting from one of the reel-bars.

The warp as it comes to the machine to be 70 there builded into warp-sections consists of many threads and assembled into a ribbon-like arrangement which may well be called a "warp-ribbon". At the beginning of the warp-building operation one of these warp-ribbons 75 is attached by a well-known method to that one of the warp-attachment pins *v* which is nearest the right end of the machine. Then the warp-reel is given rotation and synchronously the hereinbefore-described longitudinal feeding motion. This winds the warp-ribbon upon the reel to the desired height, at which point the rotation of the reel is stopped. The incoming warp is severed and the building of that particular warp-section is finished, 80 its free end being secured in a well-known method. The cross-section shape of a warp-section thus builded is indicated at *w*, Fig. 1, the reel-bars being shaped at one place to initiate this form of building the warp-section, 85 a form that may be said to have oblique edges. After the building of one warp-section in the manner already described, the machine is moved on the rails *t* until the second warp-attachment pin is in front of the path of the 90 95 100

warp-ribbon, which is then attached to the second warp-attachment pin and the second warp-section is builded in the same manner as the first. Afterward the subsequent warp-sections are builded one by one until the reel-bars are filled. When that is done, the warp-sections are ready for transference to a warp-beam.

The means for the longitudinal feed of the machine while a warp-section is being builded have already been described. The resetting of the machine longitudinally upon the rails for the building of the next warp-section is made possible by releasing the grasp of the clamp *o* upon the pinion-base *n*, thus allowing the pinion *m* to freely turn when the machine is thus reset. After the machine is thus reset the clamp *o* is again made to grasp the pinion-base, so that the rotation of the feed-worm will give the longitudinal feeding motion of the machine necessary for the building of another warp-section.

Now to describe the parts which have more immediately to do with the adjustment of the machine for building warp-sections of different widths the letter *x* denotes a bar running from end frame to end frame of the machine and moved therewith. It carries adjustably clamped thereon the arm *y*, which in turn carries adjustably clamped therein the rod *z*, standing parallel with the bar.

The letter *a'* denotes a bar suitably supported from the floor, so as to be stationary, and carrying an adjustable stop-sleeve *b'*.

The letter *c'* denotes a pawl-arm loose both rotarily and longitudinally on the bar *a'*. Its outer end carries an adjusting-screw *d'*, standing parallel with the bar *a'* and with a countersink in its head. One end of the rod *z* bears a counterpoint fitted for engagement with said countersink.

When the building of a warp-section is to begin, the rod *z*, pawl-arm *c'*, and stop-sleeve *b'* are in the position shown in Fig. 1, the pawl-arm being supported in the position there shown (as well as in Figs. 5 and 6) by the engagement of said counterpoint and said countersink. When those two parts are disengaged by the longitudinal feed motion of the machine, and hence the movement of the bar *x* and rod *d* to the left in Fig. 5, the pawl-arm drops down, as indicated in dotted lines in Fig. 6, so as to be out of the path of the rod *z* in the resetting of the machine for the beginning of the building of another warp-section. In such resetting of the machine it is moved to the right until the arm *y* strikes the hub of the pawl-arm *c'*. Then at that point the machine is held stationary, while stop-sleeve *b'* and pawl-arm *c'* are moved to the right, reset on bar *a'*, and again engaged with the counterpoint end of rod *z*, as represented in Figs. 1 and 5. Now stop-sleeve *b'* being fastened to bar *a'* and the warp-ribbon being attached to the warp-attachment-pin in front of it the building of another warp-section is ready to begin.

I claim as my improvement—

1. In a device of the character described, the combination with a longitudinally-movable frame, a feed-worm carried thereby, and means for rotating said worm; of a pinion in mesh with the worm and fast on a circular base, a clamp surrounding the latter, means for supporting said clamp, and a screw for adjusting its grasp upon the base, as and for the purpose set forth. 70

2. In a device of the character described, the combination with a longitudinally-movable frame, a feed-worm carried thereby, and 80 means for rotating said worm; of a pinion in mesh with the worm and fast on a circular base, a clamp surrounding the latter, means for adjusting its grasp upon the base, trunnions on the exterior of the clamp, and fixed 85 bearings in which the trunnions are supported, as and for the purpose set forth.

3. In a device of the character described, the combination with a longitudinally-movable frame, a feed-worm carried thereby, and 90 means for rotating said worm; of a pinion in mesh with the worm and fast on a base, a clamp surrounding the latter, a screw for adjusting its grasp upon the base, trunnions on the exterior of the clamp, a fixed plate, and 95 bearings thereon in which the trunnions are supported so as to permit rocking of the clamp and its contained base, substantially as described.

4. In a device of the character described, 100 the combination with a longitudinally-movable frame, a feed-worm carried thereby, and means for rotating said worm; of a pinion in mesh with the worm, a plate fixed with respect to said frame, a clamp carried by said 105 plate, and means for applying or releasing its grasp upon the pinion, as and for the purpose set forth.

5. In a device of the character described, the combination with a frame mounted on 110 wheels, a rotating reel whose shaft is journaled therein, a worm journaled in and traveling with the frame, and gearing between the shaft of the reel and said worm; of a pinion with which said worm is in mesh, a fixed support for the pinion, and means for controlling the rotation of the pinion in its support, 115 all as and for the purpose set forth.

6. In a device of the character described, the combination with a frame mounted on 120 wheels, a rotating reel whose shaft is journaled therein, a worm journaled in and traveling with the frame, and gearing between the shaft of the reel and said worm; of a pinion with which said worm is in mesh, means 125 for controlling the rotation of the pinion, a bar extending longitudinally of the frame, an arm adjustable thereon, and a stop with which said arm makes contact, as and for the purpose set forth. 130

7. In a device of the character described, the combination with a movable frame, a bar carried thereby and extending in the direction of its movement, and an arm adjustably

clamped on this bar; of a rod adjustably clamped in the arm parallel with said bar, a stop-sleeve, a support therefor, and a pawl thereon with which the end of the rod contacts, as and for the purpose set forth.

8. In a device of the character described, the combination with a movable frame, a bar carried thereby and extending in the direction of its movement, and an arm clamped on this bar; of a rod clamped in the arm parallel with said bar, a second bar parallel with the first and fixed with respect to the frame, a stop-sleeve adjustable longitudinally on this bar, and a movable pawl on and adjusted by the sleeve, with which pawl the rod contacts, as and for the purpose set forth.

9. In a device of the character described, the combination with a movable frame, an arm thereon, and a rod adjustably carried by this arm and standing parallel with the movement of the frame; of a fixed bar parallel with said rod, a stop-sleeve on this bar in position to engage said arm, and a pawl movably carried by the sleeve in position to engage said rod and adapted to turn transversely out of such position when the engagement is broken, as and for the purpose set forth.

10. In a device of the character described, the combination with a movable frame, an arm thereon, and a rod carried by this arm

and standing parallel with the movement of the frame, the tip of the rod having a counterpoint; of a fixed bar parallel with said rod, a stop-sleeve on this bar in position to engage said arm, a pawl pivoted and sliding on this bar against said sleeve, and an adjusting-screw through the outer end of the pawl and having a countersink adapted to engage said counterpoint, the pawl falling out of engaging position when the engagement is broken, as and for the purpose set forth.

11. In a device of the character described, the combination with a movable frame, and a rod carried thereby and standing parallel with its movement, the tip of the rod having a counterpoint; of a bar fixed with respect to the frame and standing parallel with said rod, a pawl-arm mounted loosely on said bar, means for adjusting the position of the pawl, and an adjusting-screw through its outer end having a countersink in its head adapted when in engagement with said counterpoint to hold the arm suspended but when released therefrom to permit the arm to drop out of said position in engagement with said rod, as and for the purpose set forth.
